UNITED STATES PATENT OFFICE.

RALPH B. ANNIS, OF BROOKLYN, NEW YORK, ASSIGNOR TO MOWER-GULDEN ANNIS, INC., OF BROOKLYN, NEW YORK, A CORPORATION OF NEW YORK.

DESIGN FOR A BOTTLE OR THE LIKE.

Application filed April 24, 1928. Serial No. 26,444. Term of patent 14 years.

To all whom it may concern:

Be it known that I, RALPH B. ANNIS, a citizen of the United States, and a resident of the city of New York, borough of Brooklyn, in the county of Kings and State of New York, have invented a new, original, and ornamental Design for a Bottle or the Like, of which the following is a specification.

In the accompanying drawings—

I claim:

The ornamental design for a bottle or the like as shown.

RALPH B. ANNIS.
